UNITED STATES PATENT OFFICE.

CHARLES F. HOLCK, OF LAPORTE CITY, IOWA.

DRAFT-EQUALIZER.

SPECIFICATION forming part of Letters Patent No. 351,917, dated November 2, 1886.

Application filed September 11, 1885. Serial No. 213,309. (No model.)

To all whom it may concern:

Be it known that I, CHARLES F. HOLCK, of Laporte City, in the county of Black Hawk and State of Iowa, have invented a new and Improved Draft-Equalizer, of which the following is a specification, reference being had to the annexed drawings, forming a part thereof, in which—

Figure 1 is a plan view of my improved draft-equalizer, and Fig. 2 is a side sectional elevation of the same, the section being taken on line *x x* of Fig. 1.

Similar letters of reference indicate corresponding parts in both views.

The object of my invention is to provide a simple and efficient draft-equalizer for use with four horses abreast.

My invention consists in a novel arrangement of equalizing-bars, the draft-equalizing chain extending over a sheave journaled in the frame attached to the tongue, and in novel devices for supporting the pivots of the equalizing-levers, all as hereinafter more fully described.

To the tongue *A* are secured the bars *a b*, the bar *a* projecting from the tongue at right angles, and the bar *b* connecting the outer end of the bar *a* to the tongue *A* at a point between the said bar *a* and the fastening of the tongue. Upon the bolt *c*, which connects the outer ends of the bars *a b*, is pivoted one end of the equalizing-bar *B*, the said equalizing-bar extending beneath the tongue.

To the under surface of the equalizing-bar *B*, at the free end thereof, is pivoted an equal-armed evener, *C*, carrying at opposite ends single-trees *D*, that are connected with the evener by straps *d*.

To the tongue *A*, a short distance in front of the bar *a*, are pivotally connected two bars, *e f*, by the bolt *g*. These bars extend rearwardly, and between their rear ends is pivoted one end of an equalizing-bar, *E*, upon the bolt *h*, passing through the ends of the bars *e f* and through the end of the equalizer. In the middle of the equalizer-bar *E* is inserted an eyebolt, *i*, which is connected by a chain, *j*, with a similar eyebolt, *i'*, in the middle of the equalizer-bar *B*. The chain *j* extends around

the sheave *k*, journaled in a frame, *l*, secured to the under surface of the tongue *A* near its rear end. To the outer end of the equalizer-bar *E* is pivoted the evener *C'*, whose ends are connected by straps *d'* with single-trees *D'*. Upon the bolt *g* is placed a clevis, *m*, which is connected by a chain, *n*, with a clevis, *o*, on the bolt *h*, which connects the bars *e f* and the equalizer-bar *E*. A rod, *p*, connected with a ring, *q*, encircling the forward end of the tongue, is attached to the chain *n* and clevis *m* by the ring *r*. This arrangement of the rod *p*, clevis *m*, and chain *n* limits the rearward swing of the bars *e f* and fixes the position of the inner end of the equalizer-bar *E*.

The horses hitched to the single-trees *D* are placed on opposite sides of the tongue *A*, and the draft, through the medium of the equalizing-lever *B*, the chain *j*, and the equalizing-lever *E*, is opposed to the draft of the horses hitched on the single-trees *D'*. By means of my improved arrangement of equalizing bars and chains I am enabled to secure a thorough equalization of the pull of the four horses, and to a great extent to avoid side draft.

When it is desired to apply my improvement to plows and similar utensils, the sheave *k* is removed to some portion of the frame of the plow or implement at one side or the other of the tongue *A*, in accordance with the requirements of the work to be done.

Having thus fully described my invention, I claim as new and desire to secure by Letters Patent—

1. In a draft-equalizer, the combination of the tongue *A*, provided with the bars *a b*, the equalizer *B*, pivoted at one end to the bars *a b*, the evener *C*, pivotally connected with the free end of the equalizer-bar *B*, the bars *e f*, connected with the tongue, the equalizer-bar *E*, pivoted between the bars *e f*, the evener *C'*, carried by the free end of the equalizer-bar *E*, the chain *j*, connecting the equalizing-bars *B E*, the sheave *k*, for guiding the chain *j*, and the single-trees *D D'*, connected with the eveners *C C'*, substantially as described.

2. In a draft-equalizer, the combination of the tongue *A*, provided with the bars *a b*, the equalizer *B*, pivoted at one end to the bars *a*

b, the evener C, pivotally connected with the free end of the equalizer-bar B, the bars *e f*, connected with the tongue, the equalizer-bar E, pivoted between the bars *e f*, the evener 5 C', carried by the free end of the equalizer-bar E, the chain *j*, connecting the equalizing-bars B E, the sheave *k*, for guiding the chain

j, the single-trees D D', connected with the eveners C C', the clevis *m*, chain *n*, clevis *o*, and rod *p*, substantially as described.

CHARLES F. HOLCK.
